UNITED STATES PATENT OFFICE.

GEORGE E. MOIR, OF BONAVENTURE, QUEBEC, CANADA.

SHOE-CLEANING DEVICE.

1,174,084.

Specification of Letters Patent.

Patented Mar. 7, 1916.

Application filed June 9, 1915. Serial No. 33,213.

To all whom it may concern:

Be it known that I, GEORGE E. MOIR, a subject of the King of England, residing at Bonaventure, in the Province of Quebec, 5 Dominion of Canada, have invented certain new and useful Improvements in Shoe-Cleaning Devices; and I do hereby declare the following to be a full, clear, and exact description of the invention, such as will enable 10 others skilled in the art to which it appertains to make and use the same.

My invention relates to shoe cleaning devices.

It is the purpose of the invention to provide a shoe cleaning device through the medium of which the bottom and edge of the sole and the lower portion of the upper can be cleaned with little effort and labor and at the same time thoroughly disinfected to 20 prevent the communication of any disease germs that may have become lodged upon the shoe.

It is my further purpose to provide a shoe cleaning device in which the brush elements 25 may be yieldingly held in engagement with the shoe under different pressures and in which such brush elements may be held in a fixed position and so disposed as to permit the bottom of a shoe sole to be readily engaged therewith.

It is also my purpose to provide a shoe cleaning device which will be simple in construction, efficient in use, easily applied to a door step, and which can be manufactured at 35 a relatively small cost.

With the above and other objects in view the invention consists in the details of construction and in the arrangement and combination of parts to be hereinafter more fully 40 described and particularly pointed out in the appended claims.

In describing the invention in detail reference will be had to the accompanying drawings wherein like characters of reference 45 denote corresponding parts in the several views, and in which—

Figure 1 is a front view of the invention showing the brush elements in full lines in the position they would occupy when the 50 sole of the shoe is being scraped and for the purpose of cleaning the edge of the sole and lower portion of the upper, and one of the brush elements in dotted lines in the position it would occupy when it is desired to 55 effect brushing of the bottom of the sole,

certain parts in this figure being also disclosed in section; Fig. 2, a plan view of what is shown in Fig. 1 with one of the brush elements shown in the position in which it is disclosed in dotted lines in Fig. 1; Fig. 3, a section on the line 3—3 of Fig. 1, and Fig. 4, a perspective view of one of the hinged connections between the brush elements and the base.

Referring to the drawings the invention 65 is shown as comprising a base 10 in the form of a metal plate one edge of which is provided with slits to form tongues 11. The terminal tongues 11 are bent laterally in the same direction while the intermediate tongue 70 11 is bent laterally opposite to the terminal tongues. Screws 12 are passed through respective tongues 11 and are adapted to be engaged in a porch or other desired object for the purpose of securing the invention 75 thereto. Secured to the base 10 on each side of its upper edge at the center of the latter is a plurality of V-shaped members forming radial arms 13 which in conjunction with the upper edge of the base form the scraping 80 element of the device. Pivotal connected to each side of the base 10 is a brush element A and each of these elements includes a hollow back 14 closed by a screw cap 15 and adapted to be filled with a suitable disinfecting material. A wick 16 leads from the interior of the back 14 and extends between the bristles of the brush so as to convey the disinfecting material to the bristles for distribution upon the shoe.

The hinge connection between each brush and the base 10 is indicated at B and is formed from a suitable metal blank slit and bent to produce spaced ears 17 which embrace the base 10 and securing arms 18 engaged around the brush back and united to the latter by a screw 20. Each hinge connection B has the inner ends of its ear portions provided with a plurality of openings 21 in which are adapted to be interchangeably engaged respective ends of a spring 22. The position of the openings 21 is such that when a brush element is moved to the dotted line position in Fig. 1 the tension of the spring will be exerted in a line beneath the 105 pivot of the hinge B and thus serve to hold the brush element in such position. When the brush elements are in the full line position shown in Fig. 1 the spring 22 will serve to draw the brush elements together and 110

yieldingly force the bristles thereof into engagement with the shoe so that when the latter is reciprocated between the brush elements in scraping the bottom of the sole 5 the edge of the latter and the heel will be cleaned and in addition disinfecting material will be delivered upon the shoe. The tension of the spring 22 may be varied by interchangeably engaging the ends thereof 10 in the openings 21 of respective hinge members B.

While I have described and illustrated one form of carrying my invention into practice it will be obvious that various 15 changes in the details of construction and in the arrangement of parts may be resorted to without departing from the spirit of the invention as set forth in the appended claims.

20 What is claimed is:

1. A shoe cleaning device, comprising a plate having means for attaching same to a support in upright position, radial arms secured to the plate and having their upper 25 edges in registration with the upper edge of

the plate, and brush elements secured to the plate.

2. In a shoe cleaning device, the combination of a base provided with means for attachment to a support, a bracket pivoted to 30 each side of the base, brushes carried by said brackets respectively, and a spring connecting said brackets and normally holding the latter in operative relation to a shoe supported and moved upon the base, the points 35 of connection between the spring and brackets being so disposed respectively that when the brushes are moved a predetermined distance away from each other said points will pass beneath the pivots of the 40 brackets to permit the spring to react and hold the brushes at the limit of their movement away from each other.

In testimony whereof, I affix my signature, in the presence of two witnesses.

GEORGE E. MOIR.
